United States Patent Office.

THOMAS J. FRAZIER, OF CLINTON, IOWA.

Design No. 4,059, dated May 24, 1870.

DESIGN FOR AN EMERY WHEEL.

The Schedule referred to in these Letters Patent and making part of the same.

To all whom it may concern:

Be it known that I, **THOMAS J. FRAZIER**, of Clinton, in the county of Clinton and State of Iowa, have invented and produced a new and original Design for Emery Wheel, of which the following is a specification.

The nature of my design is fully represented in the accompanying drawings, to which reference is made.

Claim.

I claim as my invention—

The design for an emery wheel, as shown

In testimony that I claim the foregoing as my invention, I set my signature in presence of two witnesses.

Witnesses:

G. R. BAILEY,
JOHN MATHEWS.
